CLAIM

We claim the ornamental design for a bottle, as shown and described.

DESCRIPTION

FIG. 1 is a perspective view of the bottle, showing our new design in full lines;

FIG. 2 is a front view thereof in full lines;

FIG. 3 is a rear view thereof in full lines;

FIG. 4 is a left side view thereof in full lines;

FIG. 5 is a right side view thereof in full lines;

FIG. 6 is a top view thereof in full lines; and,

FIG. 7 is a bottom view thereof in full lines.

The broken lines in FIGS. 1-6 are included for the purpose of illustrating a portion of the top that forms no part of the claimed design. The broken lines in FIG. 7 are included for the purpose of illustrating a portion of the bottom that forms no part of the claimed design.
